UNITED STATES PATENT OFFICE.

LOUIS H. BRUNNER, OF LAKEWOOD, OHIO.

DESIGN FOR A BADGE.

No. 38,597.

Specification for Design.

Patented June 4, 1907.

Application filed March 19, 1907. Serial No. 363,325. Term of patent 3½ years.

To all whom it may concern:

Be it known that I, LOUIS H. BRUNNER, a citizen of the United States, residing at Lakewood, in the county of Cuyahoga and State of Ohio, have invented a new and original Design of a Badge, reference being had to the accompanying drawings, forming part thereof.

The figure is a plan view of a badge showing my new design.

I claim:
The ornamental design of a badge, as shown.

LOUIS H. BRUNNER.
